JULIUS F. KINBACK, OF CARBONDALE, PENNSYLVANIA.

Letters Patent No. 87,175, dated February 23, 1869.

IMPROVED HEARSE.

The Schedule referred to in these Letters Patent and making part of the same.

To all whom it may concern:

Be it known that I, JULIUS F. KINBACK, of the city of Carbondale, county of Luzerne, and State of Pennsylvania, have invented a new Mode of Receiving Outside, and Fastening Coffins, and Placing same in Hearse.

The nature of my invention consists in a sliding platform, A, to receive the coffin outside the body of the hearse, the platform having a tongue upon either side, inserted and working in a groove in the frame B, which is attached to hearse, upon platform, the slots D and thumb-screws C movable and accessible outside hearse.

To explain my invention, so that others may make and use my invention, I construct a frame of the size of inside of hearse, the sides of which are iron, brass, or other metal, malleable or cast, or of wood, with ends of wood, with grooves running through the entire length of inside of frame. This frame is permanently fixed to the hearse, by screws or otherwise.

I then construct my sliding platform to fit the frame, with a tongue upon either side, and inserted and moving in grooves of frame, or upon rollers or casters beneath.

Upon the face of platform, I have slots D, and thumb-

screws C, accessible outside of the hearse, by means of which a coffin of any size is easily and readily fixed, and held in the exact position on the platform in which it is placed.

At the approach of bearers with coffin, I draw my sliding platform or receiver the required length from hearse, upon which the bearers place the coffin, which is fastened by the thumb-screws or otherwise, and the platform or receiver, with coffin, slid to its place.

The advantages of this platform are, the ease and celerity with which both bearers and undertaker can perform their duties at church and grave, the rapidity with which it is fitted for the road, and its safety on its journey.

What I claim as my invention, is—

The sliding platform or coffin-receiver A, working outside of hearse, in combination with frame B, thumb-screws C, and slots D, for working said platform or receiver, all constructed, arranged, and operated for the purposes set forth.

J. F. KINBACK.
